(57) **CLAIM**

The ornamental design for a hooded wrap, as shown and described.

DESCRIPTION

FIG. 1 is a perspective view of a hooded wrap;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a front elevational view of a hooded wrap in the up position;

FIG. 9 is a front elevational view of a hooded wrap in the down position;

FIG. 10 is a front elevational view of a hooded wrap shown in an up position; and,

FIG. 11 is a front elevational view of a hooded wrap in a down position.

The broken line showing of the wearer in FIGS. 10-11, and the broken line showing of a device in FIGS. 1, 2, 4, 5, 8-11, is included for the purpose of showing environmental portions and forms no part of the claimed design.
